UNITED STATES PATENT OFFICE.

CHARLES C. SPREEN, OF DETROIT, MICHIGAN, ASSIGNOR, BY MESNE ASSIGNMENTS,
TO KELVINATOR CORPORATION, OF DETROIT, MICHIGAN, A CORPORATION OF
MICHIGAN.

COMPRESSOR.

Application filed November 6, 1924. Serial No. 748,087.

To all whom it may concern:

Be it known that I, CHARLES C. SPREEN, a citizen of the United States of America, and a resident of Detroit, in the county of Wayne and State of Michigan, have invented certain new and useful Improvements in Compressors, of which the following is a full, clear, and exact description.

This invention relates to compressors, and 10 has special reference to compressors used for automatic domestic refrigerating machinery although not restricted to such use. However, the compressors employed in refrigerating machinery, in addition to being obliged to handle gases quietly and efficiently are also obliged under certain abnormal conditions to permit the passage of slugs of refrigerating liquid. In order to effect the 15 efficient and quiet handling of gases it is desirable to use very light valve members and to restrict the movement of such members to a very small degree; while to permit the passage of a body of liquid a much greater opening is necessary. The objects 20 of the present invention are the provision of an improved type of outlet valve which shall combine the features of a light and simple gas valve movable a limited distance with a heavier and more substantial liquid 25 valve movable through a greater distance; the provision of a valve mechanism of this character of such a design as can be made by stamping from sheet metal; the provision of a valve mechanism of this character in which 30 the gas valve shall consist of a flat disk of sheet metal free from wind or distortion; the provision of a valve which shall be safe against accidental displacement; while further objects and advantages of the invention 35 will become apparent as the description proceeds.

In the drawings accompanying and forming a part of this application I have shown a simple form of mechanism embodying my 45 improvements although it will be understood that the parts shown are intended to be merely illustrative of a typical form and not exhaustive as to detailed construction.

Fig. 1 is a longitudinal sectional view 50 through a part of a compressor cylinder and head having my improved valve; Fig. 2 is an enlarged central sectional view of the valve; Fig. 3 is a perspective view of the re-

lief member; and Fig. 4 is a perspective view of the valve disk.

I have shown a compressor cylinder 1 having therein a piston 2 and having its end closed by a flat plate 4 formed with an outlet port 5. Surrounding this port upon the outer face of the plate is a counterbore 6, the bottom of which exhibits a narrow integral annular upstanding flange 7 immediately surrounding the bore 5 and constituting the seat for the thin, circular, sheet-metal disk 8 which constitutes the valve.

Tightly secured to the upper face of the plate 4 is a hollow housing having an interiorly cylindrical guiding portion 10 mounted by a spring-retaining portion 11 and provided at its lower end with laterally projecting feet 12 apertured for the reception of suitable screws 13 whereby the housing is held tightly in place. Suitable means are preferably employed to keep this housing strictly in alignment with the port 5, one of the most convenient means being to continue the walls of the cylindrical portion 10 at points between adjacent feet so as to depend into the recess 6 as shown in Figs. 1 and 2. The walls of the portion 10 are also preferably formed with apertures 14 for the free escape of fluids passing through the pump and the top of the portion 11 is also preferably formed with an inwardly projecting flange 15 defining a central aperture 16 for the same purpose. This member is preferably made by standing and drawing a suitable piece of sheet metal in the manner well understood by those skilled in the art.

Slidably mounted inside the portion 10 is a relief member also preferably made of sheet metal, and comprising a cup-shaped portion having a flat bottom 18, walls 19, a flat lip 20 at the top, and a cylindrical guiding portion 21 depending from the margin 95 of said lip. The portion 21 fits slidably within the portion 10 of the housing and is formed with slots or apertures or recesses 22 for the passage of fluid. The wall 19 is also preferably formed with other passages 100 23 for the same purpose. The side wall of this member may be either considered as a cylindrical surface having holes in it, or a plurality of legs defining a cylindrical surface. The bottoms of these legs are so located relative to the surface of the portion 105

18 ~~as to afford to the valve disk 8 the limited degree of lift necessary for the passage of gas, from 5 to 8 thousandths of an inch being a very satisfactory provision. The~~ 5 diameter of the valve is such as to fit loosely inside the wall 21 which accordingly constitutes a guide therefor. The bottom face of the lip 20 constitutes a seat for a coil spring 25 which presses downwardly upon 10 the valve disk, while the top of said lip constitutes a seat for a second coil spring 26 which presses upwardly against the flange 15. The portion 11 of the housing is shown as of smaller diameter than the portion 10 15 so as to embrace the last named spring snugly though this is rather a matter of design than of necessity. The heads of the screws 13 are preferably formed with transverse apertures 28 for the reception of a 20 wire 30 by which accidental loosening of the same is prevented; the top of the plate 4 also constitutes the seat for a hollow cap member 32, tightly held in place, whose lower side is recessed to form a chamber 33 to receive 25 the compressed fluid, and the walls of this chamber by conforming to the shape of the housing and screws may further be relied upon to prevent displacement. A suitable pipe 35 communicating with this chamber 30 constitutes an outlet for the gas.

The stiffness of the spring 25 is much smaller than that of the spring 26, being made only sufficient to return the valve disk 8 promptly to its seat, this disk also being 35 preferably made of extremely small thickness and weight. In case of a rush of liquid through the pump, the increased local pressure produced thereby displaces the relief valve 20 against the tension of the spring 26, 40 thereby enabling a greater degree of unseating of the disk 8. Further the upstanding annular shape of the flange 7 permits a free and unobstructed outflow of the compressed gas laterally in all directions, thus enabling 45 free discharge of the compressor with a minimum of valve lift. This mode of housing and guiding the valve enables the use of a flat disk of maximum simplicity and lightness while the general structure of my 50 improved valve enables its production in quantity by stamping from sheet metal with a minimum of independent machining, grinding of parts, and other manipulations.

However, it will be understood that many 55 minor changes can be made without departing from my invention and that I do not limit myself except as specifically recited in my several claims.

Having thus described my invention what 60 I claim is:

1. In a gas compressor, the combination with a closure having an outlet port, said port being surrounded on its outward side by an integral upstanding annular flange, of 65 a valve disk adapted to seat on said flange

and close said port, a relief member having depending cylindrical portions surrounding said disk in guiding relation and a stop portion overhanging said disk in movement limiting relation, the walls of said relief member having outlet ports, a light spring interposed between said relief member and disk, and a second stronger spring pressing said relief member axially towards said closure. 75

2. In a gas compressor, the combination, with a closure having an outlet port, said port being surrounded on its outward side by an integral upstanding annular flange, of 80 a valve disk adapted to seat on said flange and closing said port, a housing carried by said closure and having a cylindrical guiding portion substantially coaxial with said port, a relief member slidably mounted in said housing, said relief member having portions which engage the closure member outside the said disk and other portions overhanging said disk and spaced therefrom an amount equal to the normal lift of said disk, 85 a light spring interposed between said member and disk and tending to seat the latter, and a stronger spring interposed between 90 said housing and member.

3. In a gas compressor, in combination, a member formed with an outlet port, there being a valve seat surrounding said port upon its outward side, a flat circular valve disk adapted to engage said seat, a relief member engaging said closure outside the 100 said seat and also having a central portion depending into close proximity to said disk to constitute a stop therefor, there being a recess between the outer and inner portions of said relief member, and a spring in said 105 recess pressing on said disk.

4. In a gas compressor, in combination, a closure having an outlet port and a valve seat surrounding said port upon its outer side, a thin circular valve disk engaging 110 said seat, a cup-shaped member located above said valve disk with its bottom in close proximity to such disk, its walls projecting away from said disk, its lip spaced from said disk, and a wall depending from 115 said lip past the edges of said disk into engagement with said closure, said wall having apertures therein for the passage of fluid and depending past the bottom of said cup, and a spring interposed between said disk and the lip of said cup. 120

5. In a gas compressor, in combination, a member having an outlet port and a seat surrounding said port, a housing having a cylindrical cavity substantially concentric with said port and having a spring seat beyond and substantially concentric with said cavity, means securing said housing to said closure, a circular valve disk engaging said port, and a relief member having a substantially cylindrical wall fitting 125

- slidably inside said cylindrical cavity, one end of said wall engaging said closure outside the said disk, the other end of said wall carrying a stop portion which depends into close proximity with said disk, a light spring located between said wall and stop portion and pressing upon said disk, and a stronger spring interposed between said relief member and spring seat.
6. In a gas compressor, in combination, a closure having an outlet port and a counterbore surrounding the outer end of said port, a cylindrical housing depending into said counterbore and rigidly secured to said closure, a movable relief member mounted inside said housing, a valve overlying said port, said relief member having a stopping portion spaced from its walls and projecting into close proximity to said valve, a spring surrounding said stopping portion in the space between it and the outer wall of said relief member and engaging said valve,

and a second stronger spring carried by the housing and pressing upon said relief member. 25

7. In a compressor for the purpose described, the combination of a seat member, a valve engaging said seat, a movable member having a cylindrical wall which loosely surrounds said valve and engages the seat member, said movable member also having a depending portion which extends into movement limiting relation with said valve, there being an annular cavity between said wall and said depending portion, a spring 30 located in said cavity and pressing on said valve, a fixed member secured to said closure and overhanging said movable member, and spring means interposed between said fixed and movable members and pressing said movable member toward said closure. 35

In testimony whereof, I hereunto affix my signature.

CHARLES C. SPREEN.
